CLAIM

The ornamental design for a kitchen range, as shown and described.

DESCRIPTION

FIG. 1 is a perspective view of a kitchen range showing an embodiment of our new ornamental design;

FIG. 2 is a front view thereof;

FIG. 3 is a top view thereof;

FIG. 4 is a left side view thereof;

FIG. 5 is a right side view thereof;

FIG. 6 is a perspective view of a kitchen range showing an embodiment of our new ornamental design;

FIG. 7 is a front view thereof;

FIG. 8 is a top view thereof;

FIG. 9 is a left side view thereof; and,

FIG. 10 is a right side view thereof.

The broken lines represent environment or structure and do not form a portion of the claimed design.

The bottom and rear of the kitchen range do not form a part of the claimed design.
